UNITED STATES PATENT OFFICE.

BURDETT LOOMIS, OF HARTFORD, CONNECTICUT.

PROCESS OF AND APPARATUS FOR THE MANUFACTURE OF GAS.

SPECIFICATION forming part of Letters Patent No. 404,206, dated May 28, 1889.

Application filed May 18, 1887. Serial No. 238,652. (No model.)

To all whom it may concern:

Be it known that I, BURDETT LOOMIS, a citizen of the United States, residing at Hartford, in the county of Hartford and State of Connecticut, have invented certain new and useful Improvements in Methods of and Apparatus for Manufacturing Heating or Fuel Gas; and I do hereby declare the following to be a full, clear, and exact description of the invention, such as will enable others skilled in the art to which it appertains to make and use the same.

This invention relates to the manufacture of a cheap fuel-gas having superior heating qualities as compared with producer-gas, and which is particularly adapted for manufacturing purposes—such as melting and working metals, making glass and pottery ware, firing steam-boilers, &c., and for domestic heating and cooking purposes.

I manufacture gas from cheap fuel—such as bituminous coal or slack coal—and by my method convert the oily and tarry condensable vapors ordinarily given off from such coal in producers into fixed non-condensable gas, and my finished product contains a large per cent. of combustible gases having a high calorific value, such as hydrogen, carbureted hydrogen, and carbonic oxide. I provide also for generating water-gas and conducting it off separately, either for any particularly fine work or for carbureting to form illuminating-gas. I use a down blast or draft of air for heating the fuel, whereby it is kept clear of ash and clinker, the ashes being blown into the ash-pit, which is kept hot thereby and by the outgoing hot products, thus preventing the condensation of steam when it is subsequently admitted through the ash-pit to the fuel for decomposition. Highly-heated gases resulting from decomposed steam are passed off below the surface of the fuel, so as to avoid melting and caking freshly-charged coal on top, and also to cause the rich hydrocarbon vapors and gases evolved from such coal to pass down into the heated fuel below, and thus be converted into fixed gas. I provide for passing steam up or down through the fuel, according to the state of the heat in different portions thereof. My generators are built comparatively narrow, but deep from front to back and top to bot-

tom, and are set adjacent to each other in pairs or in blocks of two to six or eight, or other larger number, as required. The producer-gas and the water-gas made at the same time in different chambers or generators of the block are mixed together in any desired proportions and conducted off through the same take-off pipe.

In the accompanying drawings, Figure 1 represents a front elevation of the generators, partly in section. Fig. 2 represents a vertical transverse section through one of the chambers and through the outlet-pipes for products of combustion and producer-gas. Fig. 3 represents a vertical transverse section through one of the chambers and the outlet-pipes for water-gas. Fig. 4 represents a horizontal section through the generators and a top view of the gas cooler and exhauster.

A represents the block of generators, composed of chambers B B' B², set adjacent to each other and separated by brick partition-walls Y and iron plates y passing through the brick and riveted to the usual iron jacket surrounding the brick walls of the generators. The generators are to be set upon piers to accommodate the gas-take-off pipes and valve-boxes arranged below. I however do not confine myself to this arrangement, as the pipes may be connected at the fronts or backs of the generators above the bases thereof.

The generating-chambers are provided with the usual grate-bars, b, and ash-pits C, and have the fire and ash doors c c' arranged above and below the grate. They are also provided at the top with fuel-openings b', having tight-fitting lids a. Passages p are formed in the tops of the chambers for the insertion of stoking or clinking bars, and these passages are closed by balls r or other suitable devices. Annular passages or flues D E F are formed in the brick walls, respectively near the top, near the middle, and near the bottom, below the grate of each generator, and are provided with numerous short ports or tuyeres, d e f, opening into the chamber, and these flues and ports or tuyeres serve for the admission of steam to, or for taking off the generated gas from, different portions of the fuel. A main steam-supply pipe, L, has a branch, L', with valve l, leading into flue D, a branch, L'', with valve l', leading into flue E, and a branch, L''',

with valve l'' , leading into flue F. An oil-supply pipe, N, having valve n , connects with branch pipe L''' , leading into flue F, or directly with such flue. A gas-take-off pipe, G, 5 for water-gas and carbureted hydrogen, connects by a short branch having a valve-box and valve, g , with flue D, and extends down and connects, by means of a horizontal branch, G'' , with the main take-off pipe O. Branch 10 G'' has at its outer end a removable lid, t , so that access may be had for cleaning the pipe, if necessary. A branch pipe, G' , having valve g' , extends upward, for conducting off water-gas independent of pipe O, which also receives 15 producer-gas. A pipe, H, having valve h , connects with annular flue E, and a branch, H' , having valve h' , connects such pipe with pipe G. The downwardly-extending pipe J and valve-box I, having ball-valve i , connects with 20 annular flue F and with pipe O by horizontal branch J' , which, at its outer end, is closed with a lid, u . An escape-pipe, K, for products of combustion, having a closing-valve, k , at its top, connects by horizontal pipe K' with 25 valve-box I, and the outer end of pipe K' is provided with a removable lid, v . Valve-box I is provided at the bottom with a seat, so that by means of ball-valve i the opening of pipe J can be closed. When the fire is being 30 repaired, valve i is closed downward, valve k is opened, and the waste products are allowed to escape up pipe K. When it is desired to pass producer-gas into pipe O, valve i is raised about half-way and suspended, when the gas 35 will pass around it and on through pipes J J into pipe O.

At the top of the generating-chamber, above the fuel-level, an annular flue, M, and ports or tuyeres m are formed in the walls, and with 40 such flue the air-supply pipe M', having controlling-valves o , is connected, so that air may be supplied to the top of the fuel for a down blast or draft. The air may be supplied by a blower, but is preferably drawn in by an ex- 45 hauster, as P, or any of the well-known kinds. Between the generator and the exhauster a tubular cooler, R, is preferably interposed for cooling the gas, so that it will not injure the exhauster. While hot gas is passed through 50 the tubes, air is circulated outside of them and heated and then flows on through pipe M' into the generator.

The operation is conducted as follows: The fires being kindled in the generators, the lids a and valves k are closed, valve i is raised and suspended, and air is supplied through flues M and tuyeres m till the bodies of fuel are highly heated. Then the air is shut off from any desired number of the generators, 55 preferably alternate ones, where sets or blocks of four or more are used, and steam is admitted to those from which the air is shut off. Before the admission of steam valve i is dropped upon its lower seat and valve g is opened. Then steam is admitted through flue F and tuyeres f , and is decomposed by passage up through the fuel and the resulting water-

gas (hydrogen and carbonic oxide) is passed off through tuyeres d , flue D, and pipe G. At the same time that steam is decomposed rich 70 hydrocarbon gas and vapors are distilled from the upper fresh layers of coal above flue D and caused to pass down into the heated fuel, where they are converted into fixed gas before escaping by way of tuyeres d and flue D. 75 If the state of the fuel is right for decomposing steam between the grate-bars and flue E, then valve g may be closed and valve h' opened and water-gas conducted by pipes H H' into pipe G. In this case the gas and vapor evolved from the upper portion of coal is caused to pass down through the heated fuel to flue E, and thereby converted into fixed gas. Should the body of fuel between flues D and E be so hot as to destructively decompose the gas and vapors evolved from the top 80 layers of coal, a small supply of steam is admitted through flue D and tuyeres d till the temperature is properly reduced. In case the temperature of the fuel is reduced too low 85 just above the grate and the heat is carried up too much by admitting steam through flue and tuyeres F f, it is shut off therefrom, valve i is opened and valves g and h' are closed, and steam is admitted to either through flue 90 and tuyeres D d or E e, or both, if desired, while gas passes off through pipe J. The heat is thus controlled and utilized to the best advantage in the different parts of the generator, and injury from a destructively 95 high heat is prevented. Steam is admitted to different portions of the generator till the 100 fuel is reduced below an effective decomposing temperature, when it is shut off, and valve i being open, that is suspended above its seats, 105 the air blast or draft is admitted through flue and tuyeres M m at the top, and the resulting producer-gas is passed off through tuyeres f, flue F, and pipe J to main O, where it 110 mingles with the hydrogen, carbureted hydrogen and carbonic oxide being generated in the other chambers. Since the air blast or draft is downward through the fuel, the oily and tarry vapors evolved from fresh bituminous 115 coal on top are carried down into the hot fuel and converted into rich fixed gas, so that the gas leaving the generator contains no condensable matter and is of superior quality for 120 heating purposes.

The mixture of water-gas and producer-gas made according to my process is much better for heating purposes than either producer-gas or water-gas alone, as ordinarily manufactured, since the water-gas is too thin and light to be consumed well at the burner and 125 since the ordinary producer-gas has not the desired calorific value and contains a detrimental percentage of non-combustible gas and impurities. By passing the blast or draft of air downward the ashes are blown into the 130 ash-pit and the surface of the fuel is kept clean, so that it will more effectively decompose steam. By passing gas from the ash-pit through the small ports f into flue F the

dust and ashes are mostly retained in the ash-pit. A block of my generators is very simple to operate and can readily be managed by one man.

5 The manufacture of gas is so conducted that usually one-half of the generators are making water-gas and carbureted hydrogen, while the remainder are making producer-gas, and the two kinds of gas are mixed in 10 the main take-off pipe. Of course the proportion of generators making water-gas can be increased or decreased at pleasure, and the quality of mixed gas thus varied and controlled as required. In case an increased 15 yield of gas is required, the plant can readily be enlarged by building additional generating-chambers upon either or both ends of the block and extending the gas and air mains and connections. When a generator is open 20 for any purpose—such as charging it with fresh fuel, removing ashes, or cleaning the fire—valve *i* should be shut down and valve or cap *k* opened, so that smoke and dust may escape up pipe *K*.

25 By exhausting the gas and thus drawing in the air to the generators workmen can much more conveniently open the top lids, *a*, to supply coal or use a bar for poking the fire, without annoyance of flame and smoke, and the 30 interior of the generator can also be inspected through the sight or peep holes *x*, to ascertain the heat and condition of the fuel, without smoke and flame being blown into the face of the operator, since the draft is inward.

35 Having described my invention, what I claim, and desire to secure by Letters Patent, is—

1. The process of manufacturing heating or fuel gas, which consists in decomposing steam 40 in contact with a body of incandescent fuel, distilling bituminous coal by contact with such body of incandescent fuel, and conducting the resulting oily and tarry vapors downward into contact with such incandescent 45 fuel, thereby converting them into fixed carbureted hydrogen gas, and at the same time generating producer-gas by the admission of air to the ignited fuel in a separate chamber, and mingling the water-gas resulting from 50 decomposed steam, the carbureted hydrogen from the distilled coal, and the producer-gas in the same main.

2. The process of manufacturing gas, which consists in decomposing steam in contact with 55 a body of incandescent fuel, thereby producing water-gas in one chamber and simultaneously generating producer-gas in a separate chamber by causing the air blast or draft to pass down through bituminous coal and 60 heated fuel, whereby oily and tarry vapors evolved from the coal are carried into the heated fuel and converted into fixed carbureted hydrogen and the producer-gas freed from condensable matter, and finally mixing 65 the water-gas and the producer-gas containing the carbureted hydrogen.

3. The process of manufacturing gas, which

consists in decomposing steam in contact with a body of incandescent fuel and distilling bituminous coal in contact with such fuel, 70 thereby producing water-gas and carbureted hydrogen and causing gas and vapor from the coal to pass in contact with the heated fuel and off below the surface of the charge for converting them into fixed gas, and simultaneously generating producer-gas in a 75 separate chamber by causing the air blast or draft to pass down through bituminous coal and heated fuel, whereby oily and tarry vapors evolved from the coal are carried into 80 the heated fuel and converted into fixed carbureted hydrogen, and finally mixing the water-gas and producer-gas and carbureted hydrogen in a pipe or chamber beyond the generator. 85

4. In combination with two or more generating-chambers, the air-supply pipes connecting with the tops thereof, outlet-pipes for producer-gas leading from the bottoms thereof, and outlet-pipes for water-gas leading from 90 the upper portions thereof, but below the level at which the charge of fuel is maintained, whereby oily and tarry vapors evolved from the fresh coal supplied to the tops of the bodies of heated fuel are caused to pass down 95 into contact with such heated fuel and thereby converted into fixed gas in both the producer-gas and the water-gas, and whereby both kinds of gas may be simultaneously generated and the manufacture of both kinds be alternated 100 in each chamber.

5. In combination with two or more generating-chambers, the air-supply pipes connecting with the tops thereof, outlet-pipes and valves for producer-gas leading from the bottoms thereof, and outlet-pipes for water-gas leading from the upper portions thereof, but below the fuel level, and a main take-off pipe, both sets of outlet-pipes connecting with the said main take-off pipe, whereby oily and 105 tarry vapors evolved from the fresh coal supplied to the tops of the bodies of heated fuel are caused to pass down into contact with such heated fuel, and thereby converted into fixed gas in both the producer-gas and the 110 water-gas, and whereby both kinds of gas may be simultaneously generated and mixed 115 in the same main for heating purposes.

6. In combination with a gas-generating chamber, the annular escape-flue *F*, located in 120 the wall below the grate, and ports or tuyeres *f*, leading from the ash-chamber below the grate into such flue, and the gas-outlet pipe connecting with such flue, whereby dust and ashes are better deposited from the outgoing 125 gas in the ash-chamber.

7. In combination with a gas-generating chamber, the flues *D*, *E*, and *F*, formed at different heights in the furnace-wall and having ports or tuyeres *d e f* opening into the 130 fuel-chamber and ash-chamber, and outlet-pipes connecting with said flues for conducting off water-gas, coal-gas, and producer-gas and leading to the main take-off pipe, whereby

gas distilled from the coal may be caused to pass down through the proper depth of hot fuel to fix the volatile vapor and be passed off at such height as to avoid destructive decomposition of such vapors by excessive heat, according to the temperature of the body of fuel and the depth thereof in the generating-chamber.

8. In combination with a gas-generating chamber having an air-supply at the top, the gas-outlet-valve box I, connecting with its base, pipes J J, connecting the valve-box with main O, ball-valve i, arranged in the valve-box to close pipe J, and escape-pipe K K, connecting with the valve-box and having a valve or cap at its top, for the purpose described.

9. In combination with a gas-generator, the outlet-pipe G for water-gas, having a valve-chamber and valve connecting with the generator near its top and with the main gas-take-off pipe for mixed water-gas and producer-gas, a separate valved water-gas pipe leading from said valve-box for conducting off water-gas alone, and a separate pipe for producer-gas leading from the bottom of the generator to said main take-off pipe, substantially as described.

In testimony whereof I affix my signature in presence of two witnesses.

BURDETT LOOMIS.
